US0D1006286S

(12) **United States Design Patent** (10) Patent No.: **US D1,006,286 S**
(45) Date of Patent: ** Nov. 28, 2023

(54) **SPOTLIGHT**

- (71) Applicant: **Zumtobel Lighting GmbH**, Lemgo (DE)
- (72) Inventors: **Harald Gruendl**, Vienna (AT); **Gernot Bohmann**, Vienna (AT); **Martin Bergmann**, Vienna (AT)
- (73) Assignee: **ZUMTOBEL LIGHTING GMBH**, Lemgo (DE)
- (**) Term: **15 Years**
- (21) Appl. No.: **35/512,875**
- (22) Filed: **Oct. 19, 2021**

(80) **Hague Agreement Data**

Int. Filing Date: **Oct. 19, 2021**
Int. Reg. No.: **DM/217086**
Int. Reg. Date: **Oct. 19, 2021**
Int. Reg. Pub. Date: **Nov. 5, 2021**

- (51) **LOC (14) Cl.** **26-05**
(52) **U.S. Cl.** **D26/63**
